CARL W. PLEHATY, OF WHITE PLAINS, NEW YORK, ASSIGNOR OF ONE-HALF TO
FRANCIS R. WHITE, OF WHITE PLAINS, NEW YORK.

CONTROLLER FOR MOTORS.

Application filed January 25, 1922. Serial No. 531,791.

To all whom it may concern:

Be it known that I, CARL W. PLEHATY, a citizen of the United States, and a resident of White Plains, in the county of West-
5 chester and State of New York, have invented a new and Improved Controller for Motors, of which the following is a full, clear, and exact description.

This invention relates to a controller for
10 motors, and has particular reference to manually operated controllers in the form of a starting box.

The main object of the invention resides in the provision of means whereby the simple moving of the handle of the starting box
15 in the usual direction will not make the proper connections.

Another object resides in the provision of means whereby an especial movement of the
20 handle of the starting box is required before the main line potential can be applied to the motor terminal.

A further object resides in the provision of means whereby if the handle of the starter
25 box is left on any of the contacts when the power is turned off, the reapplication of power will not result in any sudden flow of current through the device which will injure the various parts.

30 Another object resides in the particular construction and arrangement of parts which are hereinafter described and claimed and shown in the accompanying drawings.

The invention is illustrated in the drawing,
35 in which there is set forth a diagrammatic representation of the apparatus and circuits involved.

The drawing represents only one preferred form which the apparatus and circuits may
40 take in the embodiment of my invention in a commercial device. It is understood that various other arrangements and constructions of the parts and the character of materials used may be adapted to effect the
45 same operative principle and without departing from the scope of this invention or principle.

As shown in the drawing, this preferred representation of my invention comprises a
50 double pole switch 1 connecting power lines 2 and 3 with circuit wires 4 and 5 leading to fuses 6 and 7. Beyond the fuse a starting box is disposed. This starting box comprises a handle 8 pivoted at 9 and having on
55 its front end face contacts 10 and 11 for a

purpose hereinafter to be described. This handle is provided with a knob 12 whereby it can be moved. A plurality of contacting segments 13, 14 and 15 are arcuately disposed with respect to the pivot point of 60 the handle 8 and are adapted to be engaged by the contacting plates 10 and 11 on the end of the handle in a manner hereinafter to be described. Associated with these arcuate contacting surfaces 13, 14 and 15 are a plurality of spaced contacting fingers such as 16 and 16'. In any well known manner a plurality of resistance elements such as 17 is connected between the adjacent fingers 16'. The handle is presumed to move in the direction indicated by the arrow in the figure. It will be seen that the first segment with which it contacts is the segment 13 and that associated with this segment are three of the fingers 16. These fingers are normally 70 dead and are not normally used for the purpose of conducting any current. The segment 14 is disposed in an arc of the same circle as the segment 13 and adjacent thereto but separated electrically and mechanically therefrom. Associated with the segment 14 is a plurality of the fingers 16' and their related resistance elements 17. The right end of the segment 14 is connected in the same circumference to a plurality of 80 fingers 16' with their associated resistance elements 17. To the right of the set of fingers 16' disposed concentrically adjacent the segment 14 there is connected the segment 15.

The fuse 6 is connected by wires 18 and 19 to a contacting finger 20. The normal position of the rheostat arm 8 is shown in dot-and-dash line and is opposite the second of the dead contacts 16. The spring-pressed plug 50, hereinafter described more in detail, tends to limit the rheostat arm to this normal position of rest. In order to move it to contact with the finger 20, this plug 50 must be opposed. It will be noticed that as 90 soon as the rheostat arm leaves the finger 16 and commences to contact with the dead contact, the motor is cut off.

The rheostat handle 8 near its inner end is provided with a projection 53. Adjacent 105 this end of the handle a lever 54 is pivoted at 55. This lever carries on its outer end a bridging contact plate 56 adapted to bridge two contacts 57 and 58. Contacts 57 and 58 are disposed in the wire 27 and are bridged 110

22 by the plate 56. The other end of the lever 54 is pivoted at 59 to move in an upward direction independently of the rest of the lever from the normal position shown in the figure. The upward movement of this portion 60 of the lever 54 is limited by a stop 61. Relative downward movement of the portion 60 with respect to the lever 54 is prevented. Therefore, whenever the projection 53 bears downwardly on the portion 60, the whole lever is operated; whereas when the projection 53 tends to move the portion 60 upward it moves upwardly without effecting the rest of the lever. The wire 24 extends to a winding 25 of an electro-magnet 26, the other end of which winding is connected to a wire 27. Branched from the wire 24 is an additional wire 31 connected to a contact finger 32. This finger is adapted to be placed in circuit by the engagement therewith of a conducting end 33 of a pivoted lever 34 pivoted at 35 and electrically connected by a wire 36 with the wire 18. The lever 34 is attracted by the electro-magnet 26 having an armature plate 37 thereon. The movement of the lever 34 is cushioned by a finger 38 which is cushioned by a spring 39 disposed within a casing 40.

30 One end of a field winding 41 of the motor 29 is connected to the wire 30, and the other end is connected by a wire 42 to a field terminal 43 which is connected in turn by a wire 44 to the segment 14. The other side of the motor 29 is connected by a wire 45 to the armature terminal 46 which in turn is connected by a wire 47 to the segment 15.

40 In moving from the position of rest to the left, or in an abnormal direction, the rheostat arm or handle 8 contacts with the plug 50 backed by the spring 49 disposed in the casing 51. The plug 50 has a flanged collar 52 on its inner end, which limits its outward extension from the casing 51. When the operator moves the rheostat arm to the extreme left to contact with finger 20, it is restored to its normal position when the hand of the operator is taken therefrom by the action of the spring 49.

45 In the operation of the device, it is to be assumed that the switch 1 is closed and that the switch arm is in the full-line position shown in the figure. As soon as the switch 1 is closed, a plus potential, according to the potential representation shown in the drawing, is put on the finger 20 through wires 4, fuse 6, and wires 18 and 19. Therefore, as soon as the operator takes the switch arm, in whatever position he may find it, and moves it to the extreme left, so as to cause the switch to engage the contact 20, the following circuit is closed. This circuit extends from the switch 1, through wire 4, fuse 6, wire 18, wire 19, finger 20, arm 8, wire

24, winding 25, wire 27, contacts 58 and 57 and 56, fuse 7, wire 5, back to the other side of the line through the switch 1. This closed circuit including the winding 25, the circuit of which was closed by the movement of the switch arm 8 to engage the finger 20, will cause the energization of the winding and, consequently, the closing of switch 34. As soon as this engagement is made, the following circuit is established: from the previously established circuit through the fuse 6 and the wire 18, through wire 36, through the pivoted lever 34, the terminal 33, contact 32, through wire 24, pivot point 9 of the switch arm 8, through the switch arm 8, through contact plates 10 and 11. In a well known manner, therefore, through the finger 16' and the resistances 17 disposed between the contact plate 11 and which are in circuit with the segment 15, the armature of the motor is energized. Also and simultaneously, through the contact plate 10 being in engagement with the segment 14, the field of the motor is energized in a well known manner. Furthermore, as the switch arm 8 is moved to the right the resistance in series with the armature is cut out, while the fields for a certain movement of the switch arm are maintained constant. After the switch arm has moved off the resistance 17, concentrically arranged with respect to the segment 14, and on to the segment 15 then the resistance is entirely cut out of circuit with the armature and the other set of resistances is gradually cut in circuit with the field. This particular action, of course, is well known and need not be further described.

50 It will be noted, however, that when the pivoted switch member or plate 34 closes the contacts 33 and 32, it establishes not only a power circuit for a switch arm 8 but also establishes a holding circuit for the winding 25 as follows: from the contact 32, wire 24, winding 25 of electro-magnet 26, wire 27, fuse 7, wire 5, back to the other side of the line. As soon as the operator removes his hand from the knob 12 on the switch arm 8 the spring 49 will cause the switch arm to move just a slight distance to the right, sufficient to withdraw the arm 8 from the finger 20. This movement, however, has no effect on the magnet 25 since an independent holding circuit has been established in the manner above mentioned. Furthermore, the main circuit for the switch arm 8 has been established by the movement of the switch member 34 through a circuit which is independent of the finger 20 and contacts 56, 57 and 58. In other words, from the beginning of any operation the main power circuit through the switch arm 8 and the holding circuit for the magnet are dependent upon the closing of the circuit through the finger 20 but that after this finger has

been bridged the circuits above mentioned are established independently of this finger. Assuming that when the operator is through with the machine he opens the switch 1 without returning the arm 8 to its normal position, and happens to leave it as shown in full line position in the figure, as soon as the switch 1 is opened the holding circuit through the magnet 25 is opened, causing the deenergization of the magnet 25 and the dropping back of the armature or pivoted switch member 34. This pivoted switch member by dropping back opens the holding circuit and the main circuit as above traced, thereby automatically making the closing of these circuits thereafter dependent upon the closing of the circuits through the finger 20. By this particular arrangement and construction of the parts, it will be seen that in order to start the motor after the switch 1 is closed the operator must move the lever to an abnormal position to the left to momentarily bridge the contact 20, after which he can move the switch arm in the well known manner and speed up the motor. Furthermore, it will be observed that if he happens to leave the switch arm in any position of its travel when he shuts off the power by opening the switch 1, that the further closing of the switch 1 when he wishes to start the motor again will not cause any injury since the application of power through the switch arm cannot take place until the finger 20 has been engaged and the armature or pivoted member 34 has been turned up by the magnet 26.

Whenever the operator moves the arm 8 off the live fingers or contacts 16', as soon as the arm has left these fingers and commenced to contact with the dead fingers 16 the projection 53 on the base of the arm contacts with the end 60 of the lever 54. By thus lifting the lever the contact 56 is raised from the contacts 57 and 58 to open the wire 27. This insures that the magnet 26 is de-energized at least for a moment whenever the power arm is moved off the live fingers, even though the operator may go away and leave the switch 1 closed. When the magnet becomes deenergized the main switch or lever 34 opens and thereby disconnects the motor from the source of power and also opens the holding circuit for the magnet. However, when the rheostat arm 8 reaches the position shown in dot-and-dash line in the figure, the projection 53 has passed beyond the end 60 of the lever 54 but allows it to drop back to normal position as shown. Therefore, whenever the operator wants to energize the said magnet he moves the arm 8 as above described to contact with the finger 20, the circuit through the magnet winding having been reestablished. The movement of the arm 8 to the right will cause the engagement of the projection 53

with the end 60 of the lever, but because of the direction in which the projection is moved the end will pivot around the pin 59 to permit of the passage of the projection 53. The stop 61 will prevent the end portion 60 from reaching a position from which it would not drop back automatically. This construction prevents unnecessary energization of the winding 25 if the operator should leave the switch arm 1 in over night when the arm 8 is on the rest position.

What I claim is:

1. A motor controlling device which comprises a source of current, a rheostat having an arm, a switch, circuit connections between the above mentioned elements including the motor, said switch being normally open, said rheostat arm having normal, abnormal and operative positions, means made effective when the handle is moved to the abnormal position to effect the closing of the normally open switch whereby the power is applied to the rheostat to be applied to the motor in accordance with the further movement of the rheostat handle, and means engaging the handle when moved to its abnormal position, said means when the handle is released automatically returning it to a normal position.

2. A motor controlling device which comprises a source of power, a main power switch and a rheostat arm disposed in the circuit between the source of power and the motor, an electro-magnetic device to close said switch when energized, said switch normally being open, circuit closing means connected to the magnet and co-operating with the rheostat handle when it is moved to an abnormal position to energize the magnet and close the main switch, and circuit connections established by the closing of the switch to hold the magnet energized until the source of power is disconnected.

3. A motor controlling device which comprises a source of power, a circuit wire leading from said source to the motor, a second wire leading from said source to a main line switch, a wire leading from said main line switch to a rheostat, a wire leading from said rheostat to the other side of said motor, a shunt circuit around said main line switch, normally open contacts in said shunt circuit, said contacts disposed adjacent the arm of the rheostat and adapted to be closed thereby when the arm is moved to an abnormal position, and a magnet coil to operate the main line switch to close the same, said coil extending between one side of the line and a point in the circuit between the main line switch and the rheostat.

4. A motor controlling device which comprises a main line switch normally open, an electro-magnet to close the same, a rheostat for controlling the application of current to said motor, a circuit closing device

connected to said magnet and operated by the rheostat handle when moved reversely to an abnormal position to energize the magnet and close the main line switch, and circuit connections established by the closing of the main line switch to hold the magnet energized independently of further movement of the rheostat arm.

5. A motor controlling device which comprises a source of power, a rheostat having an arm, a switch, circuit connections between the above-mentioned elements including the motor, said switch being normally open, said rheostat arm having normal, abnormal and operative positions, means in the circuit to cause the closing of the switch when the rheostat arm is moved to its ab-

normal position, and means in the circuit automatically to cause the opening of said switch when the rheostat arm moves from the operative to the normal position.

6. A motor controlling device which comprises a rheostat having an arm, a main switch, a magnet to close the main switch when energized, circuit means for energizing the magnet when the rheostat arm is moved to an abnormal position and to establish a holding circuit for said magnet, and means actuated by the movement of the rheostat arm from operative to normal position to momentarily open the magnet circuit whenever the rheostat arm is moved from the operative to the normal position.

CARL W. PLEHATY.
